UNITED STATES PATENT OFFICE.

CLAYTON A. BROOKS, OF GIRARD, PENNSYLVANIA.

ELECTRICALLY-ACTUATED TRACK-TRIP.

1,373,595.

Specification of Letters Patent.

Patented Apr. 5, 1921.

Application filed October 29, 1920. Serial No. 420,367.

To all whom it may concern:

Be it known that I, CLAYTON A. BROOKS, a citizen of the United States, residing at Girard, in the county of Erie and State of Pennsylvania, have invented certain new and useful Improvements in Electrically-Actuated Track-Trips; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to electrically actuated track trips for railroads, particularly to that class thereof which controls the operation of trains by means of block signals.

The object of my invention is to provide trip mechanism located adjacent to the track-rails of a railway which will be electrically controlled to operate safety devices carried on moving trains, of the character shown and described in U. S. Patents Nos. 1,221,826 and 1,221,827 issued to me April 10, 1917.

In carrying out the conception of my invention I provide a normally upstanding trip to be placed in the road-bed, with spring 30 pressed means to maintain the same in an upright position so that the same may give away from the impact of a fallen brake-beam or other object not intended to be low enough to strike said trip; and I also provide motor actuated mechanism to cause said trip to be moved out of engaging position; that is, from the position of "danger" to the position of "safety", and vice-versa, to correspond to the positions of the semaphores, so that when the block-semaphore shows "safety" to allow a train to pass, the first or positive trip will be likewise moved to the "safe" position so that it will not actuate the safety device on the train, 40 and the train will not be stopped thereby.

To guard against possible breakage of the trip actuating mechanism I place a duplicate or negative trip and actuating mechanism in the road-bed a sufficient distance, say a half 50 mile away, in the direction of the traffic, and the said duplicate trips and their actuating motors are so connected by electrical conductors with a common electrical generator, and with the signal circuit of the semaphores that said trips will be alternately moved to "safety" and "danger";—that is,

the positive trip will be moved to "danger" when the semaphore shows danger, and will remain at danger so long as the semaphore does; while the second or negative trip 60 will remain at "safety" during the same period; also should the positive trip be broken down, said second or negative trip will move to danger, so that should the moving train not be stopped by the first trip it 65 will be stopped by the second trip.

The first or positive trip being at "danger" when the semaphore signals danger, and the negative trip being at "safety", when the signal circuit is deenergized to permit the semaphore to signal "safety", the motor of the second or negative trip is energized to move the negative trip to "safety", and then the motor of the positive trip is energized and moved to "danger" and vice 75 versa.

The several electrical circuits and switch mechanisms, as well as the details of trip mechanism suitable to embody my invention, are hereinafter fully described and pointed 80 out, and are illustrated in the accompanying drawings, in which:

Figure 1, is a diagrammatic view of the electric circuits and switch mechanism of my invention showing the positive trip being moved to "danger" and showing in heavy lines the circuit energized during said movement.

Fig. 2, is a like view showing the negative trip moving to "safety", and in heavy lines 90 the circuit energized during said movement.

Fig. 3, is a like view after the movements of Figs. 1 and 2 are completed and both positive and negative trips at rest in the positions indicated by broken lines in said 95 figures, none of the circuits being energized.

Fig. 4, is a like view showing the semaphore dropped to "safety", energized circuits in heavy lines, and the negative trip moving to "danger".

Fig. 5, is a like view showing the semaphore dropped to "safety", the negative trip having completed its movement to "danger" and at rest thereat, the positive trip moving to "safety" and the circuits energized during said movement.

Fig. 6, is a like view showing the energized track circuit in heavy lines while the semaphore is at "safety", both track trips at rest, and the remainder of the circuits de- 110 energized, shown by light lines.

Fig. 7, is a like view showing the ener-

gized circuit when the negative trip has been broken down, the semaphore dropped to "safety" and the positive trip moving to "safety".

5 Fig. 8, is a like view showing the energized circuits when the positive trip has been broken down, semaphore at danger, and the negative trip moving to danger instead of the positive trip.

10 Fig. 9, is a plan view of my improved trip mechanism.

Fig. 10, is a side elevation of the same with the motor mechanism removed therefrom.

15 Fig. 11, is a vertical cross-section thereof. Fig. 12, is a plan view of switch mechanism suitable for use with my invention.

Fig. 13, is an end view thereof.

Fig. 14, is a side view of the same.

20 In Figs. 9 to 11 inclusive A indicates one of the rails, and A' indicates the ties of a section of rail-road. Upon the ties A' at a desired point I secure a cross-bar A² in which is journaled a rockable tube B having secured thereon a member B' having spaced, laterally projecting ears b, b, between which is pivoted a swinging trip-arm or plate C, upon a pivot-pin C'; the end of said arm C within said ears is provided with a segment of gear teeth c (see Fig. 11) and within said tube B is a shaft or rod D provided with cylindrical rack-teeth d, which intermesh with the segmental gear teeth c on the arm C, so that a longitudinal movement of the rod D will cause said plate C to swing on the pin C' as indicated by broken lines in Fig. 11.

To give longitudinal movement to the rod D I provide a crank-shaft E upon which is placed a gear wheel E', which is engaged by a gear E², which is driven by an electric motor E³.

To maintain the trip-arm C in a vertical position as shown in Fig. 11, I provide a frame F in which the rear end of the tube B is mounted, and upon the tube B within said frame, an upright arm F' is secured. Pivoted within the frame F are bell crank levers G which cross each other under the tube B, and which have their upper ends pivoted to bars G', which bars are provided with anti-friction rollers g, which engage opposite sides of said arm F', while the lower ends of said bars G' are provided with rollers g' which rest in slots f, and between the lower ends of said bell crank levers a spring H is placed, which acts to cause said bell crank levers to force the bars G upwardly against the arm F' from opposite sides and thereby yieldingly retain it and the trip-arm C in a normally vertical position from which it may be moved by a fallen brake-beam or other like object, only to be swung back again by the spring H after such an object has passed by, the spring H,

however, having enough resisting power to operate the trip lever on the moving train intended to be operated thereby, as described in my aforementioned patents.

Within the frame F I place pairs of electric terminals I and J and place in one of the slots f a slide K which carries a plate K' which is adapted to bridge a pair of said terminals I and J; said slide K being connected to a bar G' so that if the spring H should become broken, or fail to return the arm F' to its normally vertical position, the bridge plate K' will bridge the pair of terminals J. These terminals I and J are connected to the electrical circuits hereinafter described.

Between the crank-shafts E and frames F, I place a circuit changing switch mechanism shown in Figs. 12, 13 and 14, which consists of a supporting frame L in which is placed a sliding member L', through which sliding member the rod D passes. Within said sliding member I place upon the rod D a disk d', which is adapted to engage the end walls of the sliding member, there being a suitable amount of lost motion provided for between said disk and said sliding member L'. The slide L' has, on its under side, a gear rack l with which a gear wheel L² intermeshes, said gear wheel being fixed upon a shaft L³ journaled in the frame L. Upon said shaft L³ I place a crank-arm M (see Figs. 13 and 14), from the free end of which a spring M' extends to a fastening on the frame L, so that when the free end of the crank M passes the dead center of the shaft L³, the spring M' operates to instantly throw the crank over against one of the stops M², thereby forcing the slide L' to the limit of its movement.

Upon the top of the frame (see Fig. 12) I place terminals N, N', N², N³, and P, P', P², P³; said terminals N, etc., are provided with spring contacts n which extend past each adjacent terminal P and overlap said slide L' so that at each semi-reciprocation of said slide one pair of said spring contacts n engages a pair of contacts P and P³ or P² and P³.

The diagrammatic drawings shown in Figs. 1 to 8 inclusive indicate the duplicate track trips C and their actuating mechanism as positive and negative; the positive trip being the first one to be approached by a moving train, and the direction of traffic is indicated by the heavy arrow. I also show in broken lines an ordinary semaphore Q for the purpose of explanation.

In Figs. 1 to 8 inclusive, R indicates an electric generator from which a conductor 2 leads to one side of a motor which operates the crank shaft E of a positive trip mechanism. Another conductor 3 leads from the other side of said generator to the post R' of the armature arm R² of a

relay magnet R^3 , the coil of which relay is connected with the block signal circuit S by means of the conductors 4.

S' and S^2 indicate terminals adapted to 5 be contacted by the armature arm R^2 , the spring S^3 normally maintaining the armature R^2 in contact with the terminal S' .

From the terminal S' a conductor 5 leads 10 to the post N^3 of the positive circuit changing switch mechanism, and from the contact point P^3 of said mechanism a conductor 6 leads to the other side of the motor above mentioned, so that when it is desired to move the positive trip arm C to a vertical or 15 "danger" position to correspond with the "danger" position of the semaphore, the positive switch mechanism being in the position shown in Fig. 1, the circuit will be from the generator R through conductor 3, 20 armature arm R^2 , conductor 5, spring contact n , conductor 6, motor E^3 and conductor 2, to said generator, as illustrated by heavy lines in said Fig. 1; and will so continue until the completion of a half turn of the 25 crank shaft E , when the positive trip-arm C will have completed its swing to a vertical or "danger" position, when said circuit will be broken by the action of the circuit changing switch as shown in Fig. 2.

From the post N^3 on the positive switch 30 mechanism a conductor 7 leads to a contact point P' on said mechanism, and from the post N' a conductor 8 leads to one of the terminals I in the frame F (see Fig. 10)

35 and from the other of said terminals I another conductor 9 leads to the post N^2 of the negative switch mechanism; another conductor 10 leads from the contact point P^2 of said negative switch mechanism to one

40 pole of a motor E^3 adapted to actuate the crank-shaft E , which operates the negative trip-arm C , and from the other pole of said motor E^3 , conductor 11 leads to the conductor 2, so that with the positive and nega-

45 tive switch mechanism being in their respective positions shown in Fig. 2, the circuit will be from the generator R through conductor 3, armature arm R^2 , conductor 5, conductor 7, spring contact n , conductor 8,

50 bridge plate K' (see Fig. 10), conductor 9 to the negative switch mechanism contact spring n , conductor 10 to the negative motor, conductor 11, and conductor 2 to said generator which energizes the negative motor

55 and causes its associated crank-shaft to swing the negative trip-arm C from its vertical or "danger" position to "safety," and when a semi-revolution of the negative crank-shaft is completed, the negative

60 switch mechanism L' will have broken the contact of its spring contact n from the contact point P^2 which breaks the circuit shown by heavy lines in Fig. 2, and both positive and negative trips will remain at rest as

65 long as the semaphore remains at "danger,"

as shown by Fig. 3, wherein none of the circuits are energized. It will be noted by an inspection of Fig. 3 that the positive and negative switches L' have caused the spring contacts n to contact against the negative contact posts P and P^3 , and against the positive contact posts P' and P^2 , thus forming an open circuit from the contact point S^2 at the relay through a conductor 12 to the post N^2 of the positive switch mechanism, 70 thence through the conductor 13, which extends from the contact point P^2 of said switch mechanism to the post N^3 of the negative switch mechanism; thence by the conductor 14 from the contact point P^3 of 80 said negative mechanism to conductor 10 and thence to the negative motor E^3 , and thence by the conductor 11 to conductor 2, generator R , conductor 3, post R' and relay armature R^2 . Now, when the semaphore 85 signal circuit is energized, to cause the semaphore to drop to "safety" to allow the passing of a train, the relay magnet R^3 causes the armature R^2 to close said circuit by contacting with the contact point S^2 , which energizes said circuit as shown by heavy lines in Fig. 4, which actuates the negative motor E^3 to rotate the negative crank shaft E , and thereby causes the negative trip-arm C to swing to a vertical or "danger" position 90 as indicated in Fig. 4; and when said negative trip-arm C has completed its upward travel, the circuit above described and indicated by heavy lines in Fig. 4 is broken by the negative switch L' which separates 100 the spring contact n from the negative contact P^3 . The movement of the negative switch L' opening the last described circuit allows the spring contacts n to engage the negative contact points P' and P^2 , thus establishing an energized circuit from relay contact point S^2 through conductor 12 to post N^2 of the positive switch mechanism; by conductor 13, conductor 16 to one of the terminals I in the negative mechanism 110 frame F (see Fig. 10) associated with the negative trip mechanism C , thence by conductor 17 to the post N' of the negative switch mechanism; from contact point P' of said mechanism to conductor 18, thence 115 by conductor 18 to positive motor E^3 ; thence by conductor 2 to generator R , and armature arm to relay contact point S^2 , as shown by heavy lines in Fig. 4, which energizes the positive motor E^3 , to actuate the positive 120 trip mechanism to swing the trip arm C down to "safety" as indicated by the arrow in Fig. 5.

At the end of the downward movement of the positive trip arm C , the positive switch 125 L' breaks the circuit shown by heavy lines in Fig. 5, in which condition all of the circuits remain un-energized until the semaphore circuit S is deenergized to permit the semaphore to be raised to a "safety" position, as 130

shown in Fig. 1, when the relay armature arm is released and the spring S^3 causes said arm to engage the relay contact point S' , which closes the energized circuit here- 5 tofore described and shown by heavy lines in Fig. 1, which again causes the positive trip arm C to be swung up to "danger" to correspond with the semaphore signal, and the negative trip arm to be swung down 10 to "safety" as shown by Figs. 2 and 3, and heretofore described. Thus, when a train has been stopped by the positive trip arm C being at "danger," and then released to proceed by the deenergizing of the sema- 15 phone signal circuit, the consequent closing and energizing of the circuit shown by heavy lines in Fig. 2, causes the negative trip arm C to swing down to "safety" so that the train will not be stopped thereby, 20 and thereafter said trip arm will remain at rest until the semaphore signal circuit S is again energized.

Now, should the spring H (see Fig. 10) in either of the duplicate positive or negative trip mechanisms fail to maintain the trip C in a vertical position by being broken so that the arms G' would be in the position shown in broken lines, the bridge plate K' would overlap and contact with the terminals J . In Fig. 7 the bridge plate K' is shown by broken lines as contacting with the terminals J of the negative trip mechanism, in which case there will be a closed energized circuit from the generator R 30 through conductor 3 to post R' , thence by conductor 19 to one of the negative contacts J , thence through bridge plate K' to the other of said contacts J , and thence by conductor 20 to the contact point P of the 40 positive switch mechanism, thence by spring contact n and post N of said positive mechanism, and conductor 21 to conductor 6 and thence through the positive motor E^3 and conductor 2 to the generator R which energizes said motor and causes the positive trip arm to swing upward to "danger."

At the completion of the upward swing of the positive trip arm C the above described circuit, shown by heavy lines in Fig. 7, is 50 broken by the action of the positive switch engaging the spring contacts n and lifting them out of contact with the positive contact points P and P^3 . The simultaneous contacting of the positive control points P' and P^2 does not have any effect because the negative contact terminals I are not bridged by the negative bridge plate K' so that any further action of the positive or negative trip arms ceases until the negative trip mechanism 55 has been repaired; likewise should the spring H in the positive trip mechanism become broken, and the positive trip arm remain in a horizontal position as shown in Fig. 8, the positive bridge plate K' will bridge the 60 positive terminals J , in which case the ener-

gized circuit will be from the generator R through conductor 19, conductor 22 to one of the positive terminals J , positive bridge plate K' , conductor 23 to negative post N , 70 spring contact n to magnetic contact point P , conductor 24 to conductor 14, thence through negative motor E^3 and conductor 15 to the generator, as shown by heavy lines in Fig. 8, which causes the negative trip arm C to be swung to a vertical 75 "danger" position. At the completion of said movement, the above described circuit will be broken by the lifting of the spring contact n from contact with the negative contact point P , when all of the circuits 80 will be open, and both positive and negative trips will remain at rest until the positive trip mechanism is repaired.

The object of using two trips is two-fold:

First. If the electric circuit which governs the semaphore is out of order, the trips will not change, and one of them being at "danger" the mechanism on the passing engine will be actuated, thus indicating to the engineer that the semaphore is not 90 working normally.

Second. If either one of the pair of trips should break down, the other trip will be automatically moved to, and remain at "danger," and should an engineer pass after 95 the break down, the mechanism of the engine will warn the engineer that either a train is ahead, or that the trip mechanism is out of order.

Neither trip ever moves to "safety" until 100 the other has arisen to "danger"; thus, if snow or sleet prevents the one from moving to "danger," although the position of the semaphore would normally require it to be at "safety," thus causing an unnecessary 105 action of the automatic stop of any engine passing at that time, warning the engineer that either the trips are not working properly or that a train is ahead.

My improved trip mechanism may be 110 used at certain danger points to force reduced speed, in which case they will not be electrically operated, and will have but one motion, viz:—A yielding motion to avoid breaking, should some heavy object accidentally strike them; and, to minimize the danger of breaking they can be used in pairs, as the chances of both breaking at the same time would be very small.

When a trip is used to protect an open 115 switch it will have two motions, the same as when used at a semaphore, but the vertical or horizontal position will be caused by the opening or shutting of the switch; the motion of opening or shutting the switch being 120 imparted to the trip either by an endless cable consisting of two wires, or by means of battery, motor and electric circuit between switch and trips.

From the foregoing description it will be 125

- obvious that when the semaphore circuit is deenergized to bring the semaphore to "danger" the first or positive trip arm C will be caused to swing up to a "danger" 5 position as shown in Figs. 1 and 2, and the second or negative trip arm C swings to "safety," as shown in Fig. 3. After the train has been stopped by the danger signals, and the semaphore circuit is energized 10 to move the semaphore to safety, the second or negative trip is swung to "danger," as shown in Fig. 4, and the first or positive trip swings down to "safety," as shown in Fig. 5, and the train passes onto the block 15 after which the first or positive trip swings up to "danger" as shown in Fig. 1, and the second or negative trip swings down to "safety," as shown in Fig. 2, to allow the train to pass to the next block.
- 20 Having thus shown and described suitable apparatus and mechanism to enable others to utilize my invention, I do not desire to be limited to the exact arrangement thereof shown and described, as many modifications can be made therein without departing from the scope of my invention; therefore what I claim as new is:—
- 25 1. In an apparatus of the class described, a pair of shiftable trip mechanisms positioned adjacent to the railroad track, at points distant from each other, mechanism adapted to operate each of said trip mechanisms, an electric motor to actuate each of said mechanisms, an electric generator, electric conductors connecting said generator and each of said motors, and circuit changing switches adapted to be operated by said trip operating mechanisms so that when one of said trips is moved to a vertical position 30 the other will be moved to a horizontal position.
- 35 2. In an apparatus of the class described, a pair of shiftable trips positioned adjacent to the railroad track at points distant from each other, mechanisms adapted to shift them from "safety" to "danger", an electric motor to actuate each of said mechanisms, an electric generator, a plurality of circuit breaking switches, means actuated by said trip shifting mechanisms to operate said circuit breaking switches, and electric conductors leading from said generator to said circuit breaking switches and thence to said 40 motors, whereby said motors will be alternately operated, and said trips will be alternately moved to "danger", and means actuated by an energized semaphore signal circuit to control the operation of said trip mechanisms.
- 45 3. In an apparatus of the class described, a pair of shiftable trip mechanisms positioned adjacent to the rails of a railroad track, at points distant from each other, crank-shaft and pitman mechanisms adapted to operate each of said trip mechanisms,

motor and gear mechanisms to operate said crank-shafts, an electric generator, a relay magnet connected with the usual semaphore signal circuit, circuit changing means adapted to be operated by said relay magnet, electric conductors connecting said generator with the motor at each trip operating mechanism, circuit closing and breaking switches in each mechanism, and means operated by the crank-shaft and pitman mechanisms to cause said switches to alternately open and close the circuit formed by said conductors whereby said trips are alternately moved to "safety" and "danger" when said semaphore signal circuit is energized or deenergized. 70 75

4. In an apparatus of the class described, a pair of shiftable trip mechanisms positioned adjacent to the rails of a railroad track at points distant from each other, crank-shaft and pitman mechanism adapted to operate each of said trip mechanisms, motor and gear mechanisms to operate said crank-shafts, an electric generator, a plurality of electric conductors forming open circuits from said generator through each 80 of said motors, circuit closing and opening switches associated with each of said trip mechanisms, means actuated by said crank-shaft and pitman mechanism adapted to cause some of said switches to open some of 85 said circuits and close others thereof, a semaphore signal circuit, a relay connected therewith, an armature arm adapted to be actuated by said relay to open one of said circuits and close another of said circuits when 90 said semaphore circuit is energized, whereby one of the above mentioned circuits is energized by said generator to cause one of 95 said trips to be moved to "safety", and then the other of said circuits is energized to 100 cause the other of said trips to be moved to "danger", and then the deenergizing of 105 said semaphore signal circuit causes said armature arm to open that circuit and close the other circuit to cause said trips to reverse their positions. 110

5. In an apparatus of the class described, a pair of trips positioned adjacent to the rails of a railroad track at points distant from each other, means to yieldingly maintain said trip in a vertically right angle position with relation to the traffic on said railroad, mechanism to cause each of said trips to swing from a vertical position to a horizontal position transverse of said track, 115 crank-shaft and pitman mechanism to so operate said trips, an electric motor, and gear mechanism to actuate each of said crank-shafts, a generator, circuit changing switches associated with each of said crank-shaft and pitman mechanisms, two pairs of electric terminals at each of said trip mechanisms, a bridge-plate in each mechanism adapted to bridge a pair of terminals therein and thereby close an electric circuit, 120 125 130

means to cause said bridge-plate to move from contact with one pair of terminals and bridge the other pair of said terminals when the trip is broken down in the direction of traffic, electric conductors connecting said generator and said motors through said circuit changing switches and said pairs of terminals; whereby said trips will alternately be actuated and the injured trip actuating mechanism will be cut out of circuit.

6. In an apparatus of the class described, a shiftable trip, crank-shaft and pitman mechanism to operate the same, motor and gear mechanism to operate said crank-shaft, an electrical generator, a conductor leading from said generator to a relay armature arm, a contact post, a conductor from said contact post to a circuit opening and closing switch, a conductor from said switch to said motor, and from said motor to said generator, and means actuated by said crank-shaft and pitman to open said switch.

7. In an apparatus of the class described, a shiftable trip, crank-shaft and pitman mechanism to operate the same, motor and gear mechanism to operate said crank-shaft, a generator, a conductor leading from said generator to a relay armature arm, a contact post, a conductor from said post to a circuit opening and closing switch post, a conductor from said switch post to one side of another circuit opening and closing switch, means adapted to be operated by said crank-shaft and pitman mechanism to open and close said switches, a conductor leading from the post of the last mentioned switch to the post of a circuit opening and closing switch associated with another and duplicate trip mechanism positioned at a point distant from the first mentioned trip mechanism, crank-shaft and pitman mechanism to operate the same, means adapted to be actuated by said crank-shaft and pitman mechanism to open and close said last mentioned switch, a motor to operate the same, a conductor from said last mentioned switch to said last mentioned motor, and a conductor from said motor to said generator.

8. In an apparatus of the class described, a shiftable trip, crank shaft and pitman mechanism to operate the same, motor and gear mechanism to actuate said crank-shaft, an electric generator, a relay armature arm, a conductor from said generator to said arm, a contact post to receive contact from said arm, a conductor from said contact post to a circuit opening and closing switch, and mechanism actuated by said crank-shaft and pitman mechanism to operate said switch, a duplicate trip mechanism distant from the first mentioned trip mechanism, a circuit changing switch in said mechanism, crank-shaft and pitman mechanism for operating said trip, a motor to actuate said crank-shaft, a conductor from the first mentioned

circuit opening and closing switch to a said circuit changing switch and thence to the last mentioned circuit opening and closing switch, mechanism adapted to be actuated by said last mentioned crank-shaft and pitman mechanism to open and close said switch, and a conductor from said switch to the first mentioned motor and thence to said generator.

9. In an apparatus of the class described, a rock-shaft, a normally vertical trip arm secured thereon, another vertical arm secured thereon, and spring pressed lever mechanism adapted to engage the last mentioned arm to maintain it in a vertical position.

10. In an apparatus of the class described, a rock-shaft, means to support one end thereof between a pair of railroad track-ties, a normally vertical trip arm secured thereon between the rails of a track, a frame to support the opposite end of said rock-shaft outside of said rails, an arm on said rock-shaft within said frame, and spring pressed lever mechanism adapted to engage said last mentioned arm to maintain the same in a normally vertical position.

11. In an apparatus of the class described, a hollow rock-shaft supported in suitable bearings in transverse position to a railroad track, a trip arm pivotally secured on said shaft, a longitudinally movable rod within said hollow rock-shaft, and engaging said trip arm eccentrically to its pivotal connection with said rock-shaft, an arm rigidly secured on said rock-shaft, means to yieldingly engage said arm to maintain it in upright position, and means to move said longitudinally movable rod.

12. In an apparatus of the class described, a rock-shaft, means to support the same transversely under a rail of a railroad track, a trip arm secured on said shaft inside of said rail, a bifurcated frame positioned outside of said rail to support one end of said shaft, another arm secured on said rock-shaft within said frame, and spring actuated mechanism mounted in said frame adapted to engage and yieldingly maintain said arm and trip in a vertical position.

13. In an apparatus of the class described, a trip pivotally supported adjacent to the rails of a railroad and adapted to swing from a horizontal to a vertical position transversely of said railroad track, motor actuated mechanism adapted to cause said trip to swing on its pivot, an electric generator, circuits leading therefrom to said motor, circuit changing switches, and mechanism operated by said motor actuated mechanism to open some of said circuits, and close other circuits when said trip has reached its vertical or horizontal position.

14. In an apparatus of the class described, a trip arm pivotally mounted to swing trans-

versely of a railroad track, crank-shaft and pitman mechanism adapted to operate said trip-arm, motor and gear mechanism to actuate said crank-shaft, an electric generator, 5 circuit changing switches, electric circuits from said generator to said switches and thence to said motor, mechanism operated by said crank-shaft and pitman mechanism to open some of said circuits so that said 10 motor will be cut out of circuits so as to leave the cranks of said crank-shaft on a dead cen-

ter with relation to said pitman, whereby said trip arm will be either at "safety" or "danger," and said switches will close others of said circuits, a semaphore signal circuit, 15 a relay in circuit therewith, and mechanism controlled thereby to close the last mentioned circuit, whereby said trip will be returned to danger when said semaphore is operated.

In testimony whereof I affix my signature.

CLAYTON A. BROOKS.
